UNITED STATES PATENT OFFICE

JAMES N. VERMILYA, OF CINCINNATI, OHIO, ASSIGNOR TO THE AMERICAN LAUNDRY MACHINERY COMPANY, OF NORWOOD, CINCINNATI, OHIO, A CORPORATION OF OHIO

LAUNDRY MACHINE

Application filed September 25, 1926, Serial No. 137,808. Renewed December 16, 1931.

This invention relates to laundry machines such as for washing or bleaching, and has special reference to the treatment of the fluids employed in such machines whereby the treating ingredients therein are utilized under the most effective conditions possible. Such a machine commonly consists of a generally cylindrical tub in which is arranged to rotate with periodic reversals a foraminated drum, the tub being partially filled with the treating liquid such as a soap solution or bleaching fluid, the articles to be treated being placed within the drum, rotation of which alternately submerges and drains the articles.

15 In the ordinary washing process a solution of soap and water is employed.

It is generally understood that the suds effect of the soap and water solution is produced by the formation of an emulsion film.

20 When this film is broken down during the washing process the effectiveness of the soap solution, as a detergent, is greatly reduced and the suds is said to be broken down or dead. The breaking down of the emulsion is

25 the result of a change in the physical condition of the solution, and not a chemical change. By injecting air into this solution the partially destroyed emulsion film may be built up and the broken down soap solution

30 thus revivified. Various mechanical means have been devised for reforming an emulsion film by agitation but I have found these to produce not as effective an emulsion as that formed by agitation produced by injection of air into the solution, probably since the soap particles are broken up to a much finer degree and forming a more penetrating solution when air is employed for agitation.

If steam only were injected into the solution, agitation to a much less degree would follow due to the fact that steam would be absorbed by the solution, and practically no increase in the suds would result. Moreover high temperature steam would destroy the 45 emulsion film, and to obtain any appreciable degree of agitation the use of high pressure steam would be necessary. Another considerable disadvantage in the use of steam would be its effect in raising the temperature of the 50 solution which, when treating many materials

such as for example woolen blankets, must be maintained within close temperature limits to avoid damage.

Similar advantages result from the employment of air in bleaching operations. A 55 common bleaching medium is sodium hypochlorite which under action of air releases chlorine; the chlorine in turn reacting with the water to release nascent oxygen, which effects the bleaching by oxidation of coloring matter. Hence in bleaching also, when air is employed to agitate the solution, the bleaching action is promoted. A further advance in bleaching is the use of the chlorine bearing gases in the tub in place of air, recirculating 60 the gases through the liquid in the tub.

65 The above analysis outlines advantages in the use of air resulting in a great saving of the treating materials heretofore required in accomplishing the desired operations.

The object of my invention therefore is the provision in a machine of the class described, adapted for either washing or bleaching purposes, of means for agitating the washing or bleaching liquid by injection of 70 gaseous mediums thereinto; and more particularly the invention includes means whereby compressed or atmospheric air, steam, or bleaching vapors, and/or any combination of the same may be employed as the agitating medium.

75 Further objects and advantages of my invention will be in part obvious and in part pointed out in the following description taken in connection with the accompanying drawings in which Fig. 1 is an elevation partially in section of a typical machine embodying my invention; Fig. 2, an end elevation of the same; Fig. 3, a detailed view of the piping arrangement employed as in the horizontal 80 planes of line 3-3, Fig. 1; Fig. 4, a sectional detail of the aspirator; Fig. 5, a typical section taken along the line 5-5 of Fig. 1; Fig. 6, a detailed section of the connection between the lines for the injection of atmospheric air and gases from the upper portion 85 of the machine respectively, and taken in the plane of line 6-6 of Figs. 2 and 3; Fig. 7, a detail of the atmospheric air strainer.

90 Referring now specifically to the drawings 100

the principal parts of the machine are the tub 2 supported in the frame or casing 1 and in which is mounted for rotation by suitable means not shown connecting with the gears 5 4, the cylinder or drum 3 provided with a foraminous wall to permit a treating fluid with which the tub may be partially filled, to enter the cylinder and contact with the articles to be treated therein. The tub and 10 drum are provided with suitable alignable doors through which the drum may be loaded and unloaded.

Running longitudinally across the tub beneath the drum I have provided a distributor 15 pipe 5 provided with downwardly directed rows of perforations 6 whereby whatever medium may be injected through the perforations will be evenly distributed in the treating liquid of the tub. The distributor 5 is 20 suitably maintained in position through stuffing boxes 7 and is connected at its intake end with the T 8 having a connection by means of piping including the members 9b, 9a and 9 with a steam supply controlled by a valve 10; the outlet end of the distributor is provided with a blow-off valve 24. The T 8 also connects by means of the nipple 26 with the body portion 11 of an aspirator, within which is maintained a nozzle 12 connected 25 by means of piping including the members 13 and 14a to a steam supply controlled by a valve 14.

Also connected with the body 11 of the aspirator, by means of piping including the members 15c, 15b, 15a and 15, is a strainer head 16, which permits entrance of atmospheric air to the piping 15 subject to the valve 17. Connected in the system is a compressed air line including the members 18 and 18a, 30 and valve 19, leading to piping 13 by way of a T not appearing in the drawings but located behind the piping 9 (Fig. 1), behind the piping 18 (Fig. 2) and behind the valve 14 (Fig. 3). Connected to the piping 15 35 by means of the fitting 15a, is the piping 20, 20a and 20b, controlled by valve 21, and connected with a hollow member 22 of arcuate shape having access to the upper portion of the tub.

Functioning of my invention during a 40 washing operation is as follows, assuming that the machine has been loaded with material to be washed and the proper soap and water solution provided in the tub: movement of the drum within the form will create suds and at the same time wash the clothes; after a certain length of time however the life of the solution due to its taking up dirt from the material will be decreased. To 45 revivify this suds, assuming that all the valves have been closed, the operator will normally open valves 14 and 17 allowing steam to pass through the injector nozzle 12 into the pipe 5 creating a vacuum which causes atmospheric 50 air to be drawn through the strainer head

16, and by way of piping 15 through the injector and into the washing solution through the perforations 6, at relatively high velocity, and causing the suds to be greatly increased.

If the operator desires to accomplish the injection without increasing the temperature of the washing solution he can open merely the valve 19 allowing compressed air only to accomplish the purpose; and obviously 75 where only a slight temperature rise is desired, some steam may be admitted through the valve 10 or 14 in addition to the compressed air through the valve 19.

If the temperature of the solution is too 80 low and the heat from the steam through the valve 14 is not sufficient to raise the temperature of the solution, the valve 10 may be opened to the required amount, increasing the injection temperature by the addition 85 of steam.

Assuming now that the clothes have been washed and it is desired to bleach them the tub is drained of the washing solution, which is replaced to the proper level with a solution of water and sodium hypochlorite. The valves 19 and 21 are next opened, the valve 19 admitting air into the distributor 5 under pressure. The air passing upward through the bleaching solution releases chlorine gas 90 as hereinbefore described, some of which together with the air is drawn through member 22 and piping 20 to be recirculated, the chlorine gas meanwhile combining with the water to liberate oxygen. By thus recirculating the vapors over the solution, the bleaching liquid is conserved by reclaiming chlorine gas ordinarily lost; and but a relatively small amount of bleaching liquid is required to accomplish the desired results. Of course heat 95 may be added as before, by opening of the valve 14, and air may be admitted by the valve 17 to freshen the circulating vapors.

To clean out the distributor 5 it is merely necessary that the valves 10 and 24 be opened 100 whereupon steam will pass through the pipe and out at 25 draining any foreign matter which may have become lodged within.

What I claim is:

1. In a machine of the class described, a 115 cylindrical tub adapted to be partially filled with a fabric treating liquid including soap, a foraminated drum for holding fabric emersed in the liquid in said drum and arranged for rotation, and means for injecting 120 atmospheric air into the liquid in said drum to agitate such liquid and thereby maintain a soap film thereon, said means embodying a distributor extending along the tub beneath said foraminated drum, and an injector having its outlet in communication with said distributor and its inlet in communication with atmospheric air, and means for controlling the temperature of the liquid 125 within said drum including a steam connec- 130

tion between said injector and said distributor.

2. In a machine of the class described, a cylindrical tub adapted to be partially filled with a fabric treating liquid including soap, a foraminated drum for holding fabric emersed in the liquid in said drum and arranged for rotation, and means for injecting atmospheric air into the liquid in said drum to agitate such liquid and thereby maintain a soap film thereon, said means embodying a distributor extending along the tub beneath said foraminated drum, and an injector having its outlet in communication with said distributor and its inlet in communication with atmospheric air, means for controlling the temperature of the liquid within said drum including a steam connection between said injector and said distributor, and means for removing the vapors from said tub and re-injecting them thereinto through the treating liquid.

In testimony whereof I hereby affix my signature.
